UNITED STATES PATENT OFFICE

2,381,538

MUFFLE

Henry H. Harris, Champaign, Ill.

Application July 3, 1942, Serial No. 449,643

4 Claims. (Cl. 263—47)

My invention relates to muffles or containers employed in the heat treatment of metals. In use, the muffles are charged or loaded with trays containing the metal, castings, forgings or otherwise, to be heat treated, and then are placed within a heat treating furnace. The muffles are subjected to the strains and stresses caused by the weight of the charge itself, as well as by the heat of the furnace, and have relatively short useful lives. Means such as rails or platforms are usually provided inside the muffles, upon which to support the charged trays or the like, and the weight thereof is another factor having an adverse bearing on the length of useful life of the muffle. The muffles are supported above the furnace floor or bed to permit the circulation of heat entirely around the muffle. After some use, the muffle may weaken and sag at certain points, and unless given proper support at those points, the muffle may develop cracks and shrinks, and its useful life may be too quickly terminated.

The main object of my invention, therefore, is the provision of a muffle which is structurally reinforced against the heat and weight effects resulting from use.

Another object of my invention is the provision of a muffle which has structural reinforcements therein extending both transversely and longitudinally of the muffle, the reinforcements constituting an integral part of the muffle.

Another object of my invention is the provision of a muffle which is reinforced against use conditions, the reinforcements constituting rails within the muffle.

Still another object of my invention is the provision of a muffle which has structural reinforcements therein extending both transversely and longitudinally thereof, the lengthwise extending reinforcements constituting rails forming an integral part of the muffle.

Still another object of my invention is the provision of a muffle for use within a heat treating furnace, means to support the muffle above and spaced from the furnace floor, and means to alter the distance between the muffle and furnace floor at a single point or at a plurality of points, as may be needed or desired.

A still further object of my invention is the provision of a muffle having transverse corrugations or bulges therearound, reverse corrugations or bulges on the floor of the muffle between the transverse corrugations extending longitudinally of the furnace, defining trackways between the transverse corrugations, and means to support the muffle, which supports are secured within

the recesses defined by the longitudinal bulges and between the transverse corrugations.

Further objects of my invention will be obvious from the following specification of an illustrative embodiment of my invention, and still other objects will be specifically embodiment of my invention, and still other objects will be specifically pointed out hereinbelow.

In the drawings annexed hereto forming a part hereof,

Figure 1 is a plan view of one form of muffle constructed according to and embodying my invention;

Fig. 2 is a longitudinal section thereof, on the line 2—2 of Fig. 1;

Fig. 3 is an end elevational view thereof;

Fig. 4 is a side elevational view showing my muffle disposed within a heat treating furnace;

Fig. 5 is an enlarged side elevational view of the muffle supporting mechanism;

Fig. 6 is a section on the line 6—6 of Fig. 5; and

Fig. 7 is a plan view of the trackway on which the muffle is disposed within the furnace.

My new and improved muffle as a whole is indicated by reference numeral 10, and comprises a hollow, elongated shell of generally rectangular section, the bottom or floor portion being indicated by reference numeral 12, the outwardly bowed side walls by reference numerals 14, 14, and the arched roof or top by reference numeral 16. Muffle 10 is formed of a number of individual sections 20, 20, secured together in end-to-end relationship, as will be explained below. Sections 20, 20 may be formed as by casting or otherwise of suitable high heat and corrosion resisting alloy material.

Each section 20 has formed therein a plurality of corrugations or bulges 22, 22, extending out from the body thereof circumferentially of the shell. These corrugations or bulges 22, 22 provide increased surface area for heat transfer from the furnace to the inside of the muffle, and also permit of more uniform expansion and contraction under working conditions. In addition to these strengthening, transverse corrugations or bulges 22, 22 about each section, I also provide in each section a plurality of corrugations or bulges 24, 24 extending lengthwise of the shell 10, on the floor or bottom 12 thereof between the transverse corrugations. These lengthwise corrugations 24, 24 project up into the muffle interior and have their tops flattened (see Figs. 2 and 3), and when several sections are secured end-to-end, they provide split rails extending lengthwise 55 through the muffle, upon which the material be-

ing treated may be disposed within the muffle. These internal bulges 24, 24 also serve to strengthen the muffle as well as providing increased surface area for heat transfer.

Furnaces in which muffles are employed are usually provided with either skid rails or roller rails to support the muffles, and in Figs. 4 and 5 of the drawings herein, I have illustrated a roller type of rail construction. The furnace floor or bed 50 has disposed therein two or more of U-beam rails 51, 51, within which are placed trapped roller chains 52, 52 extending lengthwise of the furnace. The tops of the cylindrical rollers 54, 54, extend upwardly of the rails 51, 51, so as to bear against and make rolling contact with the undersides of shoes 56 secured to the muffle.

Shoes 56 have flattened bottoms, with overhanging, downwardly depending skirts 58, so as to straddle the rollers 54 of rails 51. Atop each shoe bottom and integral therewith, I form a plurality of spaced skid rails 60, 60, the tops of which are upwardly angled from each side towards the center thereof. Depending downwardly from the underside of the recesses defined by the internal bulges 24, I form a plurality of integral spaced ribs 62, 62, the bottom edges of which are horizontally straight. Ribs 62, 62 oppose the upwardly angled skid rails 60, 60 (see Figs. 5 and 6) and extend transversely of the furnace length. A pair of sliding blocks 64, 64 are disposed between skid rails 60 and ribs 62. These blocks are laterally apertured (see Fig. 6) and a threaded bolt 66 is passed through a suitable opening 68 in the outer block 64, engaging a threaded opening 69 in the inner block. As the bolt 66 is rotated, blocks 64, 64 will be drawn together, riding up the inclined skid rails 60, 60 thereby raising that portion of the muffle resting thereon. Obviously, any one or more may be operated, as desired, to raise or lower any particular portion of the muffle resting thereon.

The shoe 56 is generally U-shaped in lengthwise section, and the sides thereof extend into the recess defined by bulges 24. Ears 70 are formed on each end of the shoes, about which a loop or bail 72 is passed to secure the shoes to the muffle. The ends of the loop or bail may be spot welded or otherwise secured to the muffle.

The individual sections 20, 20 are secured as by welding in end-to-end relationship, and an encircling collar 74 is provided to reinforce the joint. Stops 76 are provided near the end of each section to locate the collar 74 and secure same in position over the joint.

The ends of the muffle are flared outwardly into

flanges as 82, which may be provided with suitable closures during the heat treatment.

With my corrugation bulge construction, my muffle is provided with increased resistance to weight and heat strains and stresses. Tracks are provided as an integral part of the muffle without any appreciable increase of weight; the surface area is increased for more efficient heat transfer and any part of the muffle which needs support may receive same quickly and easily via the shoe adjustments.

Having now described my invention, what I claim and desire to secure by Letters Patent is:

1. A muffle for use in heat treating furnace comprising a casing, transverse corrugations extending entirely about the casing, and corrugations extending lengthwise of the casing on the bottom thereof between the transverse corrugations constituting work supporting rails extending lengthwise of the furnace.

2. A muffle for use in heat treating furnaces comprising a relatively elongated casing, reinforcements therein extending transversely of the casing and circumferentially thereof, and additional reinforcements extending longitudinally of the casing and between the transverse reinforcements, both sets of reinforcements comprising bulges, the transverse bulges extending outwardly from the casing, and the longitudinal bulges projecting into the casing constituting work supporting rails extending lengthwise thereof.

3. A muffle for use in a heat treating furnace and means to support same in spaced relation to the furnace floor, the muffle comprising an elongated casing having a plurality of lengthwise spaced-apart bulges extending circumferentially of the casing and outwardly therefrom, the casing also having a plurality of lines of bulges on the bottom thereof, the bulges being endwise spaced apart lengthwise of the casing and extending up into the interior thereof between the circumferential bulges, the circumferential bulges and the lengthwise bulges defining recesses to receive the casing supporting means.

4. A muffle for use in a heat treating furnace and means to support same therewithin in spaced relation to the furnace floor, the muffle comprising an elongated casing, a plurality of parallel lines of endwise spaced-apart recesses on the bottom of the casing, bulging upwardly into the interior thereof, the tops of the bulges constituting split work supporting rails extending lengthwise of the furnace, and the supporting means being received and secured within the recesses on the underside of the casing.

HENRY H. HARRIS.
